US00D896781S

(12) **United States Design Patent** (10) Patent No.: **US D896,781 S**
(45) Date of Patent: **** Sep. 22, 2020**

(54) **AUDIO ASSEMBLY**(71) Applicant: **Google LLC**, Mountain View, CA (US)(72) Inventors: **Gina Reimann**, Sunnyvale, CA (US); **Kenneth Sweet**, San Francisco, CA (US); **Luke David Mastrangelo**, San Francisco, CA (US); **Peter Michael Cazalet**, Los Gatos, CA (US); **Maj Isabelle Olsson**, Sunnyvale, CA (US)(73) Assignee: **Google LLC**, Mountain View, CA (US)(**) Term: **15 Years**(21) Appl. No.: **29/664,264**(22) Filed: **Sep. 24, 2018****Related U.S. Application Data**

(63) Continuation-in-part of application No. 29/612,920, filed on Aug. 4, 2017, now Pat. No. Des. 844,586.

(51) LOC (12) Cl. **14-01**

(52) U.S. Cl.

USPC ..... **D14/205**; D14/223(58) **Field of Classification Search**

USPC D14/205, 223; 181/129, 130, 135; 379/430, 431; 381/380, 381; 455/90.3, 455/575.1, 569.1

CPC H04R 1/10; H04R 1/1033; H04R 5/033; H04R 5/0335; H04R 1/1058; H04R 1/1041; H04R 1/1066; H04R 1/1016

CLAIM

The ornamental design for an audio assembly, as shown and described.

DESCRIPTION

FIG. 1 is a front perspective view of an audio assembly according to a first embodiment of our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a front perspective view of an audio assembly according to a second embodiment of our design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top elevation view thereof;

FIG. 14 is a bottom elevation view thereof;

FIG. 15 is a front perspective view of an audio assembly according to a third embodiment of our design;

FIG. 16 is a front elevation view thereof;

FIG. 17 is a rear elevation view thereof;

FIG. 18 is a right side elevation view thereof;

FIG. 19 is a left side elevation view thereof;

FIG. 20 is a top elevation view thereof; and,

FIG. 21 is a bottom elevation view thereof.

Broken lines are environmental only and form no part of the claimed design.
